UNITED STATES PATENT OFFICE.

WILLIAM C. SCHEU, OF LOS ANGELES, CALIFORNIA, ASSIGNOR TO HARRISON, PAUL, SCHEU CO., OF UPLAND, CALIFORNIA, A CORPORATION OF CALIFORNIA.

GAS GENERATOR.

Application filed June 18, 1921. Serial No. 478,604.

This invention relates to devices in which a combustible gas or vapor is produced from an oil. It is a well known fact that oils, and particularly petroleum oils, when highly heated, produce a vapor or gas which is inflammable, but it is difficult to prevent condensation of said vapor or gas and the attending accumulation of carbon in the heating devices and to produce a gas or vapor which will be fully consumed without the formation of soot or smoke.

Many previous inventors have sought to produce such a combustible gas or vapor by using steam under pressure to heat and atomize the oil. All such devices require the use of a steam generator or boiler and are of no value in situations where steam is not available.

It is an object of my invention to provide a gas generator in which no steam is used and which will produce a highly inflammable gas without the accumulation of carbon in the generator. A further object of my invention is to provide a generator which will form a very perfect mixture of gas and air, and by which a very perfect combustion can be produced.

With such objects in view, as well as other advantages which may be incident to the use of the improvements, the invention consists in the procedure, and in the parts and combinations thereof hereinafter set forth and claimed, with the understanding that the several necessary elements constituting the same may be varied in proportions and arrangements without departing from the nature of the invention.

In order to make the invention more clearly understood there are shown in the accompanying drawings means for carrying the same into practical effect, without limiting the improvements in their useful applications, to the particular constructions which for the purpose of explanation, have been made the subject of illustration.

Further objects and advantages will be made evident hereinafter.

Referring to the drawing which is for illustrative purposes only:

Fig. 1 is a sectional elevation on a plane represented by the line 1—1 of Fig. 2.

Fig. 2 is a section on a plane represented by the line 2—2 of Fig. 1.

Fig. 3 is a section on a plane represented by the line 3—3 of Fig. 2.

55

Fig. 4 is a fragmentary sectional view taken on the vertical plane represented by the line 4—4 of Fig. 2.

Fig. 5 is a diagram showing course of air and gases.

60

As shown in the drawing, I employ air heating and vaporizing chambers, for example, the form of rings 11 and 12 acting as circulating chambers in which air is supplied through the pipe 13 and oil supplied through the pipe 14 absorb sufficient heat to accomplish the vaporization of the fuel oil.

65

The ring 11 is provided with a threaded oil inlet 20, a downwardly faced air inlet 21, and a downwardly faced mixture outlet 22 situated adjacent to the inlet 21. The oil line 14, which is controlled by a valve 23, enters the combustion chamber 25 in which the rings 11 and 12 are situated, through the wall 26 thereof, and rising therewithin makes screwed connection with the interior of the ring 11 through the inlet 20 and projects slightly within the passage 28 of the ring to provide an oil nozzle 29.

70

The lower ring 12 is similarly provided with an air inlet 30 and upwardly faced outlets 31 and 32. The air pipe 13 delivers air from a blower 35 to the ring 12 through the inlet 30. Connecting between the inlet 21 of the ring 11 and the outlet 31 of the ring 12 is an air transfer pipe 37, and rising from the outlet 32 of the lower ring 12 is an L 40 which mounts an air nozzle 41 consisting of a vertically extending tube. Downwardly projecting from the outlet 22 of the upper ring 11 is a short nipple 45 having threaded thereupon a branch fitting 50, the body 51 of which surrounds the upper portion of the nozzle 41 and is centralized thereupon by a bushing 52. A burner cap 55 is threaded upon a nipple 56 which extends upwardly from the body portion 51 of the fitting 50.

80

The blower 35 is driven from any source such as a motor 60 and draws its supply of air from the surrounding atmosphere through a regulable intake 61 which is operated through a link connection 70 working between the control lever 71 of the valve 23 and an arm 72 extending from the damper cap 73 covering the blower intake.

85

Air furnished by the blower enters the

100

105

lower chamber or hollow ring 12 as indicated by the arrows in Fig. 3 and assumes a divided course around the ring 12, part of the air rising through the pipe 37 and entering the chamber or hollow ring 11, while the remaining air passes through the arm 40 and gains exit through the nozzle 41. A partition or obstructing web 58 separates the outlet 31 from the outlet 32 and entirely closes the interior of the hollow ring 12 therebetween. The air stream entering the hollow ring 11 must necessarily take the course therein illustrated by the indicating arrows owing to the presence of the obstructing web 80. A portion of the air rises through the pipe 37 flowing through the hollow ring 11 and a portion flows through the L 40 into the air nozzle 41.

It will be understood that when the air is turned on, the oil is also allowed to flow owing to the interconnected controls, this oil entering the hollow ring 11 through the nozzle 29 is picked up by the air current and carried through the outlet 22 into the fitting 50 from whence it flows through a hole 85 in the wall structure of the air nozzle 41, and from the downwardly projecting portion 86 of the nozzle 41 the oil drips through a hole 87 provided in a plug 88 into a fire pan 89.

In starting the burner, a quantity of oil is allowed to collect in the pan 89, and the oil collected in the pan is then lighted. The flames from the burning oil heat the chambers or hollow rings 11 and 12 and the interjoining structure to a temperature sufficient to cause the vaporization of any oil coming in contact therewith. After the heating of the parts is accomplished, the air circulating through the hollow ring 12 becomes heated and from thence passes upwardly through the air passage 37 and the nozzle 41. This air then entering the upper hollow ring 11 is subjected to still further heating action as it circulates therethrough, picking up the oil as it is excluded from the oil nozzle 29. The action of the air passing the nozzle 29 and the heated condition of the air stream causes the vaporization of the fuel which is then carried with the air into the branch fitting 50. The air and the vaporized fuel pass up into the burner cap 51 where they are combined with the flow of heated air from the nozzle 41 before being discharged through the orifices 90 and 91 provided in the cap 51.

It will be perceived that the orifices 90 are somewhat larger than the orifices 91 to provide spreading flames proportionately greater than the rising flames. After the burner is started a portion of the heat for vaporization is derived from the radiated heat absorbed through the lower ring 12, while the greater amount of heat for this purpose is gained in the upper ring 11 owing to the direct contact of the flames with the ring 11. That portion 27 of the oil pipe 14 which is contained within the combustion chamber 25

is surrounded by a heat insulating jacket 95 to prevent the premature vaporization of the oil in passing therethrough.

As soon as the burner is in normal operation, the flow of oil through the orifice ceases and heated air only is discharged through the orifice 87, this air rising and supplying secondary air of combustion to the flame from the orifices 90.

By interconnecting the air and fuel supply, I am able to simultaneously regulate both and keep their ratio fairly constant.

The outstanding feature in the practical operation of this burner generator is the almost complete absence of accumulated residue or carbon which is more or less prevalent in all previous oil burners known to me. I attain this previously unknown condition and efficiency through such an arrangement, assemblage and size of the burner parts and elements that condensation of the heated vapors is practically eliminated, therefor all of the vapors or manufactured gas is consumed in the burner and goes to supply heat for whatever purpose it is being used. In comparative tests my improved burner has shown nearly double the efficiency of competing burners of equal size and capacity on the same consumption of oil. In view of my experiments during the development of this invention and the tests above referred to, I consider the compactness and general arrangement of the parts of the burner, as shown, as going far toward permitting the results obtained, and therefor consider this arrangement and assemblage of parts as a very important part of my invention.

In my improved burner it will be noted that the passageways are quite large and unobstructed and therefor offer practically no resistance to the free movement of the materials injected therein, and owing to these large areas the gas columns are easily maintained at a comparatively uniform temperature, so there is practically no condensation and therefor no carbonization. Every particle of oil injected into my burner generator is consumed, except the base materials, which, by the intense continued heat are reduced to a very fine ash which is being continually blown out of the pipes through the burner orifices, there is consequently no residue of any description present in my burner generator after a prolonged period of use. It is mainly due to this feature of my invention that I am able to attain such remarkable efficiency in comparison with other devices of a like nature.

The invention is applicable in connection with other fuels than oils, for example, gas or coal, especially coal containing considerable volatile material, such coal, for example, in powdered form, being injected, or otherwise introduced into the chamber 11. The chamber 11 constitutes not only a vapor-

izing chamber, but also a fuel and air mixing and heating chamber, the fuel being mixed by reason of the rapid circulation of the air through the said chamber while the fuel is introduced thereinto.

I claim as my invention:

1. In combination; mechanical means for supplying air under pressure; walls forming an air heating chamber through which said air is allowed to flow; walls forming a vaporizing chamber through which the heated air from said heating chamber is allowed to flow; means for introducing oil into the current of heated air in said vaporizing chamber; a burner so placed that the combustion thereby heats said heating and said vaporizing chambers; means for delivering hot air directly from said heating chamber to said burner; and means for delivering a mixture of oil vapor and hot air to said burner from said vaporizing chamber.

2. In combination; mechanical means for supplying air under pressure; walls forming an air heating chamber through which said air is allowed to flow; walls forming a vaporizing chamber through which the heated air from said heating chamber is allowed to flow; means for introducing oil into the current of heated air in said vaporizing chamber; a burner so placed that the combustion thereby heats said heating and said vaporizing chambers; means for delivering hot air from said heating chamber to the space outside said burner to supply the secondary air of combustion; and means for delivering a mixture of oil vapor and hot air to said burner from said vaporizing chamber.

3. In combination; mechanical means for supplying air under pressure; walls forming an air heating chamber through which said air is allowed to flow; walls forming a vaporizing chamber through which the heated air from said heating chamber is allowed to flow; means for introducing oil into the current of heated air in said vaporizing chamber; a burner so placed that the combustion thereby heats said heating and said vaporizing chambers; means for delivering hot air directly from said heating chamber to said burner; means for delivering hot air from said heating chamber to the space outside said burner to supply the secondary air of combustion; and means for delivering a mixture of oil vapor and hot air to said burner from said vaporizing chamber.

4. In combination, an air heating chamber, a fuel and air mixing and heating chamber, a burner located in position to heat said air heating and mixing chambers, and means for supplying air under pressure to said air heating chamber, means for conducting a portion of the air from said air heating chamber to the mixing chamber, means for conducting another portion of air from said air heating

chamber to said burner, means for supplying fuel to said fuel and air mixing and heating chamber, and means for conducting a mixture of fuel and air from said fuel and air mixing and heating chamber to said burner.

5. In combination, an air heating chamber, a fuel and air mixing and heating chamber, a burner located below and adjacent to said last named chamber and above said first named chamber so as to heat both of said chambers, said fuel and air mixing and heating chamber being connected to receive heated air from said air heating chamber and having an outlet connection for conducting a mixture of fuel and air to said burner, and said burner having an air inlet connection for supplying air directly thereto from said air mixing chamber, means for supplying air to said air mixing chamber, and means for supplying fuel to said fuel and air mixing and heating chamber in the path of the air passing through said chamber from said air heating chamber to said burner.

6. In combination, an air heating chamber, a fuel and air mixing and heating chamber located above said air heating chamber and connected to receive air therefrom, a burner connected to receive a mixture of fuel and air from said fuel and air mixing and heating chamber and adapted to heat both of said chambers, a connection from said air heating chamber to supply air from said chamber directly to said burner and a fuel supply pipe communicating with the fuel and air mixing and heating chamber, said pipe having a heat insulating covering to protect it from the heat of the burner.

7. A generator burner comprising two hollow rings of large cross sectional area and having partitions therein and being placed in superposed relation, means for admitting air into one of said rings and a gas producing material into the other of said rings, means for combining said air and a gas from said fuel in one of said rings to form a combustible mixture, means for conveying said mixture to burner members where it is consumed and caused to heat said hollow rings, said hollow rings and connecting means having free and unobstructed passageways whereby the accumulation of carbonaceous residues is obviated.

8. An apparatus for combining air and oil and converting them into a burning mixture comprising a pair of spaced hollow members of large cross sectional area, one of said members serving as an air distributing chamber, the other of said members serving as a fuel mixing chamber, the air distributing chamber having an air inlet with means for feeding air thereto, and two air outlets, the mixing chamber having an oil inlet, an air inlet and a mixture outlet, a burner member, large cross sectional area pipe means connecting said burner member with said air chamber

and said mixing chamber whereby air and a combustible mixture are conveyed to said burner member for consumption thereby, with means for preheating said members and means for supplying air and oil.

9. An apparatus for manufacturing a combustible gas mixture from air and a gas making material comprising a pair of hollow rings having large cross sectional area superposed one over the other, large cross sectional area pipe means connecting said rings for the passage of air, and other large area pipe means connecting said rings for the passage of a combustible mixture from one ring and air from the other ring, a burner member connected to receive said mixture and air and consume them, the relation of said rings and said burner being such that the heat of combustion will maintain a generating temperature in the said assembly to continue the production of a burning mixture with means for preheating said assembly to start operation with means for supplying air to one of said rings and oil to the other said ring.

10. An apparatus for manufacturing a combustible gas mixture from air and a gas making material in a manner to prevent the formation and accumulation of carbonaceous

materials from said mixture comprising a large section hollow ring serving as an air distributing chamber, an air inlet in said ring and two air outlets with an imperforate partition between the outlets, a large section hollow ring serving as a mixing and combining chamber, an inlet for gas making material, and an inlet for air from the air distributing chamber with an imperforate partition between the air inlet and an outlet for the combined mixture, a burner member located adjacent said ring members, said burner member being connected to receive the mixture from the mixing chamber and to receive air from the air distributing chamber whereby the mixture is consumed, means for preheating the assembly for starting operation, the pipe connections for said rings and said burner all being of large section to prevent a chilling of the mixture and the formation of carbonaceous material as mentioned during the continuous generation of gas from the action of said burner.

In testimony whereof, I have hereunto set my hand at Los Angeles, California, this 13th day of June, 1921.

WILLIAM C. SCHEU.
